UNITED STATES PATENT OFFICE

170,736

COMBINED FOOD AND BEVERAGE VENDING STATION

Louis A. Zon, Buffalo, N. Y.

Application January 23, 1953, Serial No. 23,263

Term of patent 14 years

(Cl. D13—1)

To all whom it may concern:

Be it known that I, Louis A. Zon, a citizen of the United States of America and residing at Buffalo, in the county of Erie and State of New York, have invented a new, original, and ornamental Design for a Combined Food and Beverage Vending Station, of which the following is a specification, reference being had to the accompanying drawings forming part thereof.

Fig. 1 is a perspective view of a combined food and beverage vending station embodying my new design, this view being taken from a point in front of and slightly above the station.

Fig. 2 is an elevational view of the front thereof.

Fig. 3 is a side elevational view thereof, viewed from the right of the station as shown in Fig. 2, the left hand side being similar in appearance.

Fig. 4 is a top plan view thereof.

Fig. 5 is an elevational view of the rear thereof.

I claim:

The ornamental design for a combined food and beverage vending station, substantially as shown.

LOUIS A. ZON.
